ANTI-ROLL STAY FOR WAISTBANDS OF GIRDLES
AND LIKE ARTICLES OF APPAREL
Americo Marchisella, % Rago Foundations, Inc.,
18-15 27th Ave., Long Island City, N.Y.
Filed Oct. 11, 1963, Ser. No. 315,498
9 Claims. (Cl. 128—533)

This invention relates to a stay for preventing the roll of waistbands of girdles and like articles of apparel, the upper edges of which terminate at a wearer's waist.

It is an object of this invention to provide a new and improved stay which is so integrated into a garment that it will prevent the upper marginal areas, i.e. the waistbands, of girdles and like articles of apparel from rolling, twisting and flexing in an undesired manner while being worn by a woman.

It is a common and well recognized problem which is particularly aggravating in the women's undergarment industry, that the upper edges of such apparel tend to turn, roll over or twist while in use in a manner which is both unattractive and uncomfortable to the wearer. This problem is magnified in garments which are partially or wholly elastic and snugly fit the torso of the wearer in order to shape or constrain the form of the body. The upper or waist edges of such articles, since they constitute a marginal portion of a flexible and usually resilient material, obtain the least support from the remaining structure of the garment and so can be forced out of shape most easily. In cases where the wearer has an excess of fatty flesh on her body, the upper edges have the function of supporting a weight and volume which overtaxes their strength. When engirdled by a tightly fitting garment, the excessive outer avoidupois on the waist is often forced upward so as to overhang and to weigh upon the upper leading edge of such an article, tending to overturn and displace these upper edges, again contributing to their poor appearance.

Further, articles of wear such as girdles often lose some of their strength after several washings so that while in a sense not worn out or excessively used, the article loses, at least at its upper edge, its normal form-maintaining ability long before the article needs otherwise to be discarded.

To prevent the rolling, turning or other distortion of the upper edges of such articles it is desired to present a new and improved stay that in a novel manner stiffens these areas against rolling, distributes the excessive strain placed on the upper edges of such garments, and adds to the useful life of these articles by reinforcing their structures.

To this end, spaced circumferentially extending stays constructed in accordance with the present invention are seated within a fabric tunnel adjacent the waistline of and parallel to the upper edge of the article, one stay being situated at each flank of the wearer. That is, the stays lie in a horizontal plane and, when the garment is worn, are constrained by the tunnel that at this time encircles the waist to define the vertices of an ellipse which circumscribes the waist of the wearer. Both stays thereby assume a significant degree of outwardly convex curvature, i.e. bowing, which consequently prevents the waistband of the garment to which they are attached from rolling since for the thusly stayed garment to roll one or both ends of a stay would have to be tilted out of the tunnel.

It is another important object of my invention to provide an anti-roll stay of the character described which stiffens the portion of the article to which it is attached and which by virtue of the location of a pair of stays on diametrically opposed locations on the girdle serves as a

handle, one on each side of the garment, to aid in donning the garment. The stays make marginal portions of the garment more firm and thereby provide convenient grips for the hands of the wearer while pulling on the garment.

5 The stress in the girdle material caused by stretching it over the hips is distributed by the stays over a large portion of the marginal area of the garment.

It is yet a further object of the invention to provide an anti-roll stay of the character described which will with 10 a mild degree of pressure tend to spring radially outwardly about a point centered on the flank of the wearer and which will therefore moderate pressure at the tips of the stay located in the softer and more sensitive areas around the wearer's waist. Although the lessening of 15 pressure on the abdomen and back will increase the pressure at the hip of the wearer, this latter pressure is more readily sustained in a comfortable manner by the human body.

These and various other objects and advantages of my 20 invention will become apparent to the reader in the following description.

My invention accordingly consists in the features of construction, combinations of elements and arrangements of parts which will be exemplified in the form constraining 25 undergarments hereinafter described and of which the scope of application will be indicated in the appended claims.

In the accompanying drawings in which are shown two 30 of the various possible embodiments of my invention,

FIG. 1 is a left-side perspective view of a girdle with stays captured within its waistband, the stays being illustrated in dash lines;

FIG. 2 is a greatly enlarged fragmentary and partially 35 broken away view of the stay in a tunnel at the girdle waistband;

FIG. 3 is an enlarged transverse cross-sectional view taken substantially along the line 3—3 of FIG. 2;

FIG. 4 is a top plan schematic view of the upper edge 40 of the girdle showing the position of the stays; and

FIG. 5 is a view similar to FIG. 2 but showing a second embodiment of my invention.

Referring now in detail to the drawings, the reference 45 numeral 10 denotes a stay constructed and mounted on an article of women's underclothing in accordance with my invention. The stay is made from a flexible resilient material which is sufficiently thick to require at least a few ounces of pressure applied to the ends of the stay to significantly flex the same. Polyethylene, a resilient butadiene modified polystyrene, whalebone, spring steel and 50 similar materials have been found entirely suitable for this purpose. The stay 10 is preferably flat and is elongated, and desirably has its end edges or tips 12 rounded so that no sharp points or corners are present to damage the material from which the garment is made. By way of 55 example, suitable dimensions for the stay are about 6 to 12 inches in length, about $\frac{1}{2}$ to 1 inch in width, and about $\frac{1}{32}$ to $\frac{1}{16}$ of an inch in thickness. The stay is springy and has a resiliency and will, in a situation of repose, assume a normally flat elongated non-curved (linear) 60 condition, but yet upon slight force will conform to another desired, curved shape. It should be noted that at this point that such stays are, as thus far described, entirely conventional.

It is a characteristic of such stays that in an unbent 65 form they have two flex axes, the first being about a vertical axis parallel to the plane in which the width (height in the drawings) of the stay lies and transverse to the length of the stay. That is to say, the stays flex in a manner to define a severer or milder curvature as their 70 ends move toward and away from one another (compare FIGS. 2 and 5). The second axis is a longitudinal or torsion axis and also lies in the plane of the width of the

stay but along the length of the stay. The stay can thus twist on itself with one end moving, say clockwise, and the other end moving counter-clockwise.

The stay 10 due to its great length compared with its relatively small width will flex more readily about its first-named axis and, as will shortly be seen, this characteristic is employed by the present invention to enhance the anti-roll quality of the stay.

The stay may have a feathered symmetrical construction, with the thickness of its upper edge 14 and lower edge 16 tapering away from its mid-thickness. (See FIG. 3.) In other words, the upper and lower edges of the stay are narrower in cross-section than its middle thickness. This configuration has sufficient thickness to inhibit flexing of the stay about its torsion axis while the feathered edges 14, 16 use less material so as to maintain the light weight of the stay. The feathered shape of the edges helps them blend in and so not protrude from their fabric housing.

The stay is captively secured to the waistband 18 of a girdle 20 or like article of wearing apparel. The girdle 20 to which my stay 10 is attached is conventional and, as is usual, has circumferentially elastic front and back panels E, and, optionally, one or more non-elastic panels N, and it is contemplated that such stays may also be applied to any constrictively ensheathing article of apparel with an at least partially circumferentially elastic waistband, such as panties, garter belts, slacks with upper elastic edges, trunks of two piece bathing suits, stretch pants, etc. Any article of clothing which experience has demonstrated will, due to the elastic or engirdling nature of its waistband area, tend to roll may benefit from the present invention.

A pair of stays is located on the waistband 18 of the girdle 20 so that one stay is situated on each flank of the wearer. The center of the stay is located approximately at the midpoint of the flank area, i.e. at a point at which a line drawn vertically downward from the shoulder of the wearer would intersect an ellipse outlining her waist. Each stay extends in a circumferential direction substantially equidistantly from this center point toward the front and back of the wearer, each half of the stay preferably being of similar length. The tips 12 of the stays terminate at points short of the front and rear center lines of the wearer. That is, the tips of the stays do not touch one another but rather provide a definite and substantial interruption where they approach one another both at the front and rear of the waistband 18 of the girdle 20. Each stay therefore has a shape corresponding to an end section of an ellipse at a vertex thereof.

Each stay 10 is captively held in an elastic fabric flat tunnel 22 formed on the waistband 18 of the girdle 20. The tunnel is preferably constructed of elastic material. The tunnel 22 may be continuous around the entire circumference of the waistband 18 or it may be terminated at points distant from the tips 12 of the stays 10.

The tunnel 22 is formed in part by an elastic binding 24 which is continuous around the waistband 18, and which is stitched to an upper margin 26 of the waistband. The margin 26 has a free edge 28 which is turned over inwardly on itself to present an attractive and finished looking fold 30. The binding 24 is sewn flat to the margin 26 so that one row of stitching 32 passes through the upper edge of the binding 24 and into the free edge 28 and so that another parallel row of stitching 34 passes through the lower edge of the binding 24 and into an adjacent area of the margin 26. The binding 24 covers the raw edge of the garment so as to present a neat appearance in this area as well as to form the tunnel 22. The height of the tunnel 22 is such that it snugly captures the stays 10, that is to say, the tunnel is of a height small enough to inhibit movement in a vertical direction of the stays and yet large enough to allow ease of entry of the stays during assembly. The rounded tips 12 of the stays aid in the insertion of the stays into the tunnel to their proper loca-

tion. The tunnel is narrow so as to prevent radial movement of the stay 10 therein.

The stays are secured in the tunnel and to the garment by mechanical anchoring means so that each stay will remain at a different flank of the garment. In the illustrated embodiment a vertical bar tack 36 is sewn directly through the stay 10 and into the binding 24, it being understood that in this instance the stay is formed from a plastic, e.g. polyethylene or other material which will permit such stitching. The bar tack fixes the longitudinal center of the stay at the appropriate center of the flank of the wearer. (See FIG. 5.)

In a second embodiment of my invention, the stay 10 has a preformed aperture 38 disposed longitudinally centrally of the stay. Stitching 40 passes through the aperture 38 both upwardly and downwardly over portions of the stay and then into the binding 24. In FIG. 5, the waistband 18 is illustrated in a flat position of repose.

As is most clearly shown in FIGS. 1 and 4, each stay 10 when the girdle 20 is donned by the wearer is arched, i.e. assumes a relatively sharp horizontal curvature. The assumption of such a curvature inhibits the stay from twisting or rolling about its horizontal axis, and the curvature also stiffens the stay 10 against vertical flexing and rolling. The waistband 20 of the girdle will not therefore roll, turn or twist on itself, with the stays giving support to the major portion of the waistband. The stays 10 being in a horizontal position will not dig into the wearer, as is often the situation with vertically oriented stays.

If the garment is stretched in any direction the tips 12 of the stays 10 merely move forwardly or rearwardly completely within the tunnel 22 and thereby do not abut and cannot catch against any surface. The stays 10, of course, are prevented from shifting and are maintained in their most useful position at the flanks of the wearer by the stitching at their center, although the girdle, as well as the tunnel 22, may stretch considerably.

Since the stays 10 are of a stiffer material than that of which the girdle is made and further since they are disposed with their longitudinal axes disposed circumferentially of the girdle, they serve as convenient handles by which the girdle may be gripped and by which it may thereafter be pulled upward over the hips of the wearer. The stiffness of the stays presents firm areas of the girdle that may be held by the wearer, and the length of the stays distributes the stress placed thereon over a large portion of the waistband 18. This prevents undue ripping of the girdle material, either by the fingers of a woman poking through the girdle material or by high local stress on the material.

The stays 10, due to their natural resiliency, are biased from their curved position toward their flat position in repose. The halves of each stay attempt to swing radially outwardly about the point at which they are attached to the girdle 20, i.e., the stitching 36 (or 40). This tendency of the tips relieves the pressure from the girdle 20 against the back and abdomen of the wearer (FIG. 4, arrow "A") and places additional pressure against the flank of the wearer (FIG. 4, arrow "B"), where it can be borne more comfortably.

It thus will be seen that I have provided devices which achieve the several objects of my invention and which are well adapted to meet the conditions of practical use.

As various possible embodiments might be made of the above invention, and as various changes might be made in the embodiments above set forth, it is to be understood that all matter herein described or shown in the accompanying drawings is to be interpreted as illustrative and not in a limiting sense.

Having thus described my invention, I claim as new and desire to secure by Letters Patent:

1. In combination with a garment having a constrictive upper margin at the waist, a horizontal circumferential flexible tunnel secured to the garment adjacent its upper

margin, a flat continuous solid normally flat thin flexible resilient stay of substantially rectangular transverse cross-section and formed from sheet material, said stay being located in said tunnel and having its length elongated circumferentially of the upper margin of the garment, said length being substantially greater than the height of the stay and said height being substantially greater than the thickness of the stay, said stay having its length extending a substantial distance on either side of the flank toward but terminating short of the front and rear centers of the garment, and means anchoring the stay within the tunnel and in a position spanning the flank area of the garment so that when the garment is donned the stay assumes a substantial curvature around the flank whereby to inhibit the margin from rolling.

2. A combination as set forth in claim 1 wherein the tunnel is continuous around the margin and wherein two diametrically opposed stays of like length are provided, each spanning a different flank area.

3. A combination as set forth in claim 1 wherein two diametrically opposed stays of like length are provided, each spanning a different flank area.

4. A combination as set forth in claim 3 wherein the anchoring means includes stitching sewn directly through the centers of the stays and into adjacent portions of the garment.

5. A combination as set forth in claim 3 wherein each stay has a preformed aperture and wherein the anchor-

ing means includes stitching sewn around the stays, through the apertures and into adjacent portions of the garment.

6. A combination as set forth in claim 3 wherein the tunnel is narrow and of a height substantially the same as the height of the stays so that the tunnel snugly receives the stays.

7. A combination as set forth in claim 3 wherein the stay has a transverse symmetrically feathered construction, the top and bottom edges of each stay being narrower in cross-section than the middle portion of the stays.

8. A combination as set forth in claim 1 wherein two diametrically opposed stays of like length are provided, each spanning a different flank area, and wherein the anchoring means fixes the center of each stay to the center of a different flank area of the garment.

9. A combination as set forth in claim 1 wherein the stay has a length of from about 6 inches to about 12 inches.
